US0D1109134S

(12) **United States Design Patent** (10) **Patent No.:** **US D1,109,134 S**
(45) **Date of Patent:** **** Jan. 13, 2026**

(54) **CELL PHONE CASE WITH CARD HOLDER**

(71) Applicant: **Hamee Global Inc.**, Seoul (KR)

(72) Inventors: **Bum Joon Lee**, Seoul (KR); **Yeeun Son**, Incheon (KR)

(73) Assignee: **HAMEE GLOBAL INC.**, Seoul (KR)

(**) Term: **15 Years**

(21) Appl. No.: **35/523,914**

(22) Filed: **Jul. 30, 2024**

(80) **Hague Agreement Data**

Int. Filing Date: **Jul. 30, 2024**

Int. Reg. No.: **DM/243805**

Int. Reg. Date: **Jul. 30, 2024**

Int. Reg. Pub. Date: **Feb. 7, 2025**

(30) **Foreign Application Priority Data**

Jul. 10, 2024 (KR) 30-2024-0027302

(51) **LOC (15) Cl.** **03-01**

(52) **U.S. Cl.**

USPC **D14/250**; D3/249
